United States Patent Office

Des. 215,450
Patented Sept. 30, 1969

215,450

BOWLING SCORE PIN

Leon P. Ried, 301 N. Denison St.,
Baltimore, Md. 21229

Filed July 17, 1968, Ser. No. 12,798

Term of patent 14 years

Int. Cl. D11—03

U.S. Cl. D29—2

FIG. 1

FIG. 2

FIG. 3

FIG. 4

FIGURE 1 is an isometric view of a bowling score pin showing my new design;

FIGURE 2 is an elevational front view;

FIGURE 3 is an end view;

FIGURE 4 is a sectional view thereof taken on line 4—4 of FIGURE 2.

The dominant features of my design reside in the portions shown in full lines.

I claim:

The ornamental design for a bowling score pin, as shown and described.
